(57) CLAIM

The ornamental design for footwear, as shown and described.

DESCRIPTION

FIG. 1 is a first side view of footwear showing my new design;

FIG. 2 is a second side view thereof;

FIG. 3 is a top side perspective view thereof;

FIG. 4 is a front view thereof;

FIG. 5 is a rear view thereof;

FIG. 6 is a top plan view thereof; and,

FIG. 7 is a bottom plan view thereof.

The elements shown in fine dashed lines represent unclaimed portions of the footwear in which the design is embodied and form no part of the claimed design.
